Attorney.

UNITED STATES PATENT OFFICE.

LEOPOLD ADERT, OF BERLIN, GERMANY.

ALTERNATING-CURRENT METER.

Application filed August 10, 1920. Serial No. 402,737.

To all whom it may concern:

Be it known that I, LEOPOLD ADERT, a citizen of Germany, and resident of Berlin, Germany, have invented a certain new and useful Improved Alternating-Current Meter (for which I have filed applications in Germany, December 31, 1918, Patent No. 321,168; Holland, May 5, 1920, Patent No. 9,141; Hungary, May 31, 1920, Patent No. 78,924; Denmark, August 20, 1920, Patent No. 31,226; England, July 12, 1920, Patent No. 151,245; Belgium, June 30, 1920, Patent No. 288,100; France, July 1, 1920, Patent No. 518,495; Italy, June 29, 1920, patent not yet granted; Sweden, June 4, 1920, Patent No. 55,092; Switzerland, June 8, 1920, Patent No. 89,572; Spain, June 30, 1920, Patent No. 74,272; Austria, June 8, 1920, Patent No. 86,335; Czechoslovakia, June 21, 1920, Patent No. 6612), of which the following is a specification.

The present invention broadly refers to alternating current meters and it has for its object to provide a driving system for electrical meters constructed on the Ferraris principle for measuring alternating and three phase currents, with a considerable turning moment, low consumption in the shunt circuit, and adequate proportionality for all loads throughout the whole range of measurement.

The original method of carrying the principle into effect is represented by the known driving system comprising a pressure or field magnet core in the shape of a C and a U shaped electro-magnet, for example, similar to those described in German patent specifications 215,194 and 295,665. In the drawings affixed to this specification and forming part thereof, a device embodying my invention is illustrated diagrammatically by way of example.

In the drawings

Figure 1 is a side elevation of the pressure magnet core, while

Figures 2 and 3 are a side elevation and front elevation respectively of the rotor and the magnets combined therewith.

In accordance with this present invention, a third leg is provided on the pressure magnet core, so as to obtain an m-shaped upper part. The free end of the leg which embraces the driving disc is made to extend in front of the third leg so as to constitute an

opposing pole to it. a is the three-legged pressure magnet, with its winding b provided on the middle leg. The rotor c is located in the air-gap between the legs which are of equal length and the leg which extends past their ends. The said rotor is traversed by the lines of force of the pressure magnet at two points spaced sufficiently apart from each other to permit two polar fields to act upon the driving disc in opposite directions. Their power ratio can be varied within certain limits by means of a magnetic bridge piece d located between the two legs of substantially equal length. This may be accomplished for example by moving the said bridge piece nearer the middle or nearer the outer leg. In order to provide for exact compensation and to ensure a 90° phase difference between the main current field and the pressure field an adjustable sheet metal piece h made of copper or of some other conductive material is provided, the said sheet being, whenever necessary, introduced into the air gap between the upper leg of the magnet core and the magnetic bridge piece d. The U-shaped core e of the series coil f is placed on the side of the rotor opposed to the pressure magnet. The result is that two current actuating fields of opposite sign are formed, one on each side of the leg of the pressure magnet carrying the pressure coil. 85

As that leg of the pressure magnet embracing the rotor provides for a good return circuit for the flow of magnetic lines of force, the driving action of the pressure field suffices to permit a sufficiently high torque to be obtained by use of the main current winding generally employed for any driving system for meters.

Now whenever the number of turns of the main current coil is increased, more powerful current fields and, as a result, a higher torque are secured. However, under ordinary circumstances the number of turns could not be increased because, owing to the super-saturation of the iron core, which takes place prior to reaching the upper load limit of the meter, the registration will decrease in the upper range of the measuring action of the meter. This drawback is eliminated by exerting on the rotor a driving action in the opposite direction by aid of the third leg which, according to the invention, has been added to the pressure magnet in consequence

of the mutual action of the current field and the field of the third leg of the pressure magnet.

The two pressure fields being spaced apart from each other, each of the two legs of the U-shaped main current core is provided with angular iron members g and g' these members forming the main current driving fields of different signs on either side of the pressure field and producing the counter torque.

Now, the partial counter torque, which is used as a correcting device for providing compensation for the defective indications of the meter, operates by reason of a considerable fall, which occurs in the magnetizing curve of the counter torque system, whenever the load is being increased, in comparison with the magnetizing curve of the forward torque system, since the cross sectional area of iron of the two angular pieces g and g' has been so determined and so formed, that they become magnetically saturated when the meter is running at half load, so that on a further increase in the load, there is no substantial further increase, in the counter torque, which therefore remains practically constant.

As a result the correcting device effects a decrease in the indications given by the meter within the lower range of measurement, and this consequently permits to secure a sufficient proportionality of the data indicated by the said meter for all loads.

I claim:—

1. An electric current meter, comprising a rotor and a pressure magnet core disposed radially with regard to said rotor, two radially juxtaposed legs forming part of said core and extending substantially at an angle to said rotor, and a third angular leg on said core, part of said third leg extending in parallel, another part at right

angles to said two legs substantially in parallel with and close to the opposite side of said rotor.

2. An alternating current meter comprising a rotor, a substantially m-shaped pressure magnet with an air gap partly embracing said rotor and means adapted to cooperate with said magnet for creating two pole fields separated from each other and acting on said rotor in opposite senses.

3. An alternating current meter comprising a rotor, a substantially m-shaped pressure magnet with an air gap partly embracing said rotor, means adapted to cooperate with said magnet for creating two pole fields separated from each other and acting on said rotor in opposite senses and a magnetic bridge displaceably disposed between the parts of said magnet which create the pole fields.

4. An alternating current meter comprising a rotor, a substantially m-shaped pressure magnet with an air gap partly embracing said rotor, means adapted to cooperate with said magnet for creating two pole fields separated from each other and acting on said rotor in opposite senses, a magnetic bridge displaceably disposed between the parts of said magnet which create the pole fields, and a piece of conductive sheet metal adjustably arranged in the air gap between said bridge and one of said parts.

5. In an alternating current meter a pressure magnet core, comprising an m-shaped portion, a transverse leg attached to an end of and extending below said portion, a U-shaped main current magnet core embracing said transverse leg and an angular piece of iron arranged on either leg of said U-shaped core.

LEOPOLD ADERT.
